WALL CONSTRUCTION

Theodore R. Drake and Leroy Rosswell Huston,
Long Beach, Calif.

Application December 4, 1948, Serial No. 63,556

10 Claims. (Cl. 20—4)

1

This invention relates generally to building structure and relates more particularly to wall structures.

While the invention may be used for other purposes it is shown and described herein as a wall structure for buildings.

It is an object of the invention to provide a wall structure which may be continuously fabricated in standardized sections of such lengths as may be desired, the sections being transported to the building site and erected or incorporated into the structure being built. The sections may be cut to lengths at the building site as required.

Another object of the invention is to provide a structure of this character which may be quickly installed or erected and secured so that the framework of the building may be put up very rapidly and easily.

Still another object of the invention is to provide a structure of this character the parts of which may be continuously assembled, glued-welded and finished as to size. The finished structure may be coated or dipped with a preservative which is termite and moisture proof.

A further object of the invention is to provide a structure of this character having grooves which will take care of the glue and keep it from running and/or smearing.

A still further object of the invention is to provide a structure of this character wherein window and door openings may be incorporated as the structure is fabricated.

Another object of the invention is to provide a structure of this character wherein the window and door openings are of such character that the window and door frames may be precision fit and put in at the location. The installation of such window and door frames may be easily and quickly effected.

Still another object of the invention is to provide a structure of this character wherein the window and door openings may be provided with suitable reinforcing as the structure is manufactured or fabricated.

A further object of the invention is to provide a structure of this character whereby wall junctions at the ends of sections and intermediate said ends may be easily and quickly made, said junctions being of simple and strong construction.

A still further object of the invention is to provide structure of this character much of which may be made of short pieces of lumber. Hence, a low grade of lumber may be used. When using the low grade of lumber the knots and other

defects may be cut out so that the short pieces which are incorporated into the structure are clear or substantially clear of knots and defects. This makes possible a structure of extremely low cost as to materials. Also it is possible to secure well dried and seasoned lumber.

It is another object of the invention to provide a structure of this character having window frames with effective draining and sealing means.

Another object of the invention is to provide structure of this character which is simple in construction, extremely sturdy and relatively inexpensive to manufacture.

Other objects and advantages of the invention will be brought out in the following part of the specification.

Referring to the drawings which are for illustrative purposes only.

Fig. 1 is a side elevation of a wall structure embodying the present invention;

Fig. 2 is a partial plan as viewed from line 2—2 of Fig. 1;

Fig. 3 is a partial enlarged section taken on line 3—3 of Fig. 1;

Fig. 4 is a partial enlarged section taken on line 4—4 of Fig. 1;

Fig. 5 is a partial enlarged section taken on line 5—5 of Fig. 1;

Fig. 6 is a partial enlarged section taken on line 6—6 of Fig. 1;

Fig. 7 is a partial enlarged section taken on line 7—7 of Fig. 1;

Fig. 8 is a side view of the lower end of a window frame embodying improved sill pan for draining water which may seep through the adjacent joints of the frame;

Fig. 9 is a section taken on line 9—9 of Fig. 8; and

Fig. 10 is a section taken on line 10—10 of Fig. 9.

Referring to Fig. 1, the wall construction is shown as a framework formed by a bottom plate 15 and a top plate, indicated generally at 16, and comprising a piece 17 laid flatwise, and a piece 18 laid edgewise. The plates are relatively thick pieces which run continuously lengthwise of the structure. There are also relatively thin stringers 19 which extend longitudinally and continuously lengthwise of the structure and are parallel with each other as well as the upper and lower plates 15 and 16. The structure also includes studding which extends laterally between the plates and which are vertically disposed when the structure is erected in the building. Each studding comprises short studding

55

blocks 20 which extend between adjacent longitudinally extending parts. For example, the lower studding block extends between the bottom plate and the adjacent stringer 19 and abuts against said plate and stringer. The studding blocks are of substantially the same width as the stringers 19 and on each side of the studding blocks are vertically extending studding members 21 which extend from the under side of the lower plate 15 to the upper side of the upper plate member 17. The plate members 15 and 17 are notched to receive the adjacent end portions of the studding members (Figs. 1 and 2). The thickness of the studding blocks is greater than the width of the studding members, and projects on each side thereof as indicated at 22 (Figs. 1 and 5), thereby forming grooves 23, the purpose of which will be explained hereinafter.

Fire walls, or fire stops, are provided in the structure and comprise longitudinally extending members 24 which are of substantially the same width as the plate members 15 and 17 and are used in place of the stringers which would otherwise be used in the respective locations in the structure. The fire stop members 24 are notched to receive the vertically extending studding members 21 (Figs. 1 and 6), and it is to be noted that two fire stops are used in the structure, said fire stops being spaced transversely apart. The fire stops are of substantially the same thickness as the stringers and extend parallel with said stringers which, of course, are spaced laterally or vertically apart in the structure. It will be apparent that because of the vertical or lateral spacing of the stringers and fire stops between the upper and lower plates and the longitudinal spacing of the studdings, a framework is formed having open spaces or bays 25.

The structure may also have window or door openings formed therein during the process of fabrication or manufacture. By way of example, a window opening 26 is shown, one of the studdings having a portion removed so as to provide an opening of sufficient width to accommodate the window. At the top of the window opening a header 27 is provided (Figs. 1 and 4), which extends lengthwise across the window opening and fills bays of reduced size formed by having a stringer 19 spaced closer to the stringer at the top of the window opening than the usual spacing of the stringers. The header reinforces the opening and, of course, if the structure is of such character as to require additional reenforcing at the upper end of the window opening, an additional header may be provided across the bays immediately above the header 27. In some buildings it may be necessary to provide additional headers and these may be incorporated in the same manner as the header 27. It is to be noted that the header is of substantially the same thickness as the studding blocks 20. At the bottom of the window opening is a lower head 28 which may be of the same width as the header 27 or may be of reduced width as shown.

It is to be understood that the header 28 may be either above or below the adjacent stringer and may be of different widths to meet the requirements of a particular window or windows. It is also to be understood that the size and location of the upper stringer may be varied according to the requirements of the building, and if desired, the upper and lower headers may run continuously lengthwise of the wall structure.

Should a door opening be required such opening may be provided in a manner similar to the window opening 26. The header 27 is used at the top of the door opening but the lower header, adjacent stringer 19, and the studding extending from said adjacent stringer 19 to the lower plate, is eliminated. The threshold of the door is attached to the lower or bottom plate 15, between the sides of the door opening.

In fabricating or manufacturing the structure, the parts are continuously assembled on a suitable conveyor, glued, and the glue welded by well-known glue welding means, so that the entire structure is easily and quickly assembled and permanently glue welded together into an extremely strong wall. The grooves 23 take care of any glue which may be squeezed from between the adjacent surfaces of the vertically extending studding members and stud blocks, so that the squeezed-out glue will not run over substantial areas of the parts or become smeared thereon. It is also to be understood that the structure may be coated, dipped, or otherwise treated with termite or waterproof preservatives, or other suitable preservatives, after said structure has been fabricated. Many of the pieces, such as the studding blocks 20, may be cut from low grade lumber which is relatively inexpensive, so that the material costs are low. The stringers 24 may also be cut from low grade lumber and spliced, with the splices glue welded. By using this method, knots and other defects of the low grade lumber may be cut out so that the finished wall structure is formed of clear lumber. Hence, clear lumber is provided in continuous strips, and the sections may be run out in considerable lengths. The sections may be as long as desired, compatible with handling equipment.

Means for joining the sections at the corners is provided, and as shown (Figs. 1, 2 and 3), comprises square corner posts 30 which have longitudinally extending grooves 31 in each side. The groove of one side receives the flange-like extension 22 of the end studding to provide a snug secure fit, and the corner post and adjacent studding are secured together by means of bolts 33 (Fig. 3). The end studding of the adjacent wall which extends transversely or at right angles to the section secured to the corner post, as above described, is similarly secured to said corner post; the flange 22 of the studding of the transverse section is received in a groove 31 of the corner post on the desired side thereof and is bolted to said corner post by means of a bolt 34.

There is also means provided for joining a transverse wall intermediate the ends of a section, and said means comprises a corner backing board 35 (Figs. 1 and 4), which has a longitudinally extending groove 36 on the outer face thereof. The corner backing board 35 extends from the under side of the plate 15 to the under side of the plate 15 which is suitably notched to receive said backing board. The backing board 35 may be glue welded to the top and bottom plates, as well as to the stringers 27 and fire walls 24, which are also suitably notched to receive said backing board. The end studding of the transverse wall, as best shown in Fig. 4, may also be glue welded to the backing board. The flange 22 of the end studding is received in the groove 36 of the backing board so that the vertically extending studding members 21 abut against the outer face of the corner backing board adjacent the groove. Thus, a secure connection is made between the wall structures.

The window frame is adapted for ready installation in the window opening, and as shown in Figs. 8, 9 and 10, comprises side pieces or jams 40, a top member, not shown, of usual construction, and a sill 41. Each end of the sill is grooved at 42, said groove running from the front edge of the sill to the rear edge, and is adapted to receive a trough portion of a sill pan. Each sill pan comprises the aforementioned top portion formed in the general shape of a U, as indicated at 43, and an upstanding portion 44 at the outer side. The window casing, when installed, includes a stucco molding 45 which is slotted at its lower end to receive the upstanding portion 44 of the sill pan. The lower end of each studding at the sides of the window opening, are notched at 46 so that the sill pan portion 44 will lie against the adjacent studding block 20.

The lower side of the sill is contoured and provided with a seating surface 47 which rests on the stringer above the lower header 28, or if the header 28 is disposed above the stringer, said sill portion 47 rests on said header.

It will be apparent from Fig. 8 that the U-shaped portion of the sill pan is received in the groove 42 and is protected against crushing or deforming by the portion of the sill beneath said groove. Hence, it will be apparent that the sill pan cannot be crushed or otherwise damaged by installation of the window frame in the window opening, so that its effectiveness cannot be impaired. Further, the window frame may be installed with a precision fit and will include the conventional parts such as the casing 48, window stop 49, and groove 50, for the parting stop.

Another novel feature of the window frame comprises a metal line stop 51, which is formed of sheet metal and includes a generally U-shaped portion 52 and laterally extending flanges 53. A seal 54 of suitable paper or the like, of well-known type, has a marginal edge portion clamped between the arms of the U-shaped portion 52, and the free edge portion of the strip of paper 54 overlaps the adjacent portion of the building wall to thereby provide a weatherproof seal between the wall and the frame.

In installing the blind stop, one flange 53 is received in a groove provided therefor in the outer edge of the jams, and the other flange 53 is snugly received in a groove provided therefor at the inner side of the stucco molding 45. The closed side of the U-shaped portion 53 of the blind stop extends inwardly of the jams and functions in the usual manner.

We claim:

1. A wall construction, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, each studding member comprising stud blocks extending between the stringers and between the plates and adjacent stringers, and a studding piece on each side of said blocks extending continuously between said plates; and means for securing the various parts together.

2. A wall construction, comprising: a pair of longitudinally extending plates spaced apart and parallel with each other; a plurality of longitudinally extending, substantially parallel stringers spaced apart from each other and from the plates; a plurality of transversely extending sub-

stantially parallel studding members spaced apart longitudinally relative to the plates, each studding member comprising stud blocks extending between the stringers and between the plates and adjacent stringers, and a studding piece on each side of said blocks extending continuously between said plates, the various parts being secured together by glue.

3. A wall construction, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, each studding member comprising stud blocks extending between the stringers and between the plates and adjacent stringers, and a studding piece on each side of said blocks extending continuously between said plates, said studding blocks being wider than the studding pieces so as to project outwardly thereof; and glue means for securing the various parts together.

25 4. A wall construction, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, each studding member comprising stud blocks extending between the stringers and between the plates and adjacent stringers, and a studding piece on each side of said blocks extending continuously between said plates, said studding blocks being wider than the studding pieces so as to project outwardly thereof; and glue means for securing the various parts together.

30 40 5. A wall construction, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, each studding member comprising stud blocks extending between the stringers and between the plates and adjacent stringers, and a studding piece on each side of said blocks extending continuously between said plates, the various parts being secured together by glue; and an upper header extending between at least a pair of studdings separated sufficiently to provide an enlarged opening, said header being of substantial width and lying between and glued to a pair of stringers.

60 6. The invention defined by claim 5, wherein there is a bottom header of substantial width at the bottom of said opening and extending at least between said pair of studdings.

7. A frame structure of the character described, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, including at least one end stud member, each studding member comprising stud blocks extending between the stringers and between the plates and adjacent stringers, and

a studding piece on each side of said blocks extending continuously between said plates, said studding blocks being wider than the studding pieces so as to project outwardly thereof; glue means for securing the various parts together; a corner post having a plurality of sides, at least two of said sides having grooves therein in one of which a portion of said end studding member is received; and means for securing said corner post to said adjacent studding member.

8. A frame structure of the character described, comprising: a pair of longitudinally extending plates spaced apart and parallel with each other; a plurality of longitudinally extending, substantially parallel stringers spaced apart from each other and from the plates; a plurality of transversely extending substantially parallel studding members spaced apart longitudinally relative to the plates, each studding member comprising stud blocks extending between the stringers and between the plates and adjacent stringers, and a studding piece on each side of said blocks extending continuously between said plates, said studding blocks being wider than the studding pieces so as to project outwardly thereof; glue means for securing the various parts together; and a corner backing piece extending transversely of the frame, substantially parallel with the studding, and having the lower end received in a notch provided therefor in one of the plates, said corner backing piece having a longitudinally extending groove at a lateral side thereof.

9. A wall construction, comprising: a pair of longitudinally extending plates spaced apart and parallel with each other; a plurality of longitudinally extending, substantially parallel stringers spaced apart from each other and from the plates, at least one of said stringers being the same width as the plates to provide a fire wall; a plurality of transversely extending substantially parallel studding members spaced apart longitudinally relative to the plates, each studding

member comprising stud blocks extending between the stringers and between the plates and adjacent stringers, and a studding piece on each side of said blocks extending continuously between said plates, said studding blocks being wider than the studding pieces so as to project outwardly thereof; and glue means for securing the various parts together.

10. A wall construction, comprising: a longitudinally extending bottom plate; a longitudinally extending upper plate in parallel spaced relation to the bottom plate, said upper plate comprising a member lying in the plane of the wall and a second member disposed outwardly thereof and lying at substantially right angles thereto in abutment therewith; a plurality of longitudinally extending substantially parallel stringers spaced laterally apart and substantially parallel with the plates; and a plurality of studding members extending transversely between the plates, said studding members being substantially parallel with each other and spaced apart longitudinally relative to the plates, each studding member comprising stud blocks between the respective stringers and plates, and a studding piece on each side of said blocks and extending across the wall, the various parts being glued together.
